UNITED STATES PATENT OFFICE.

MARIANNE BENDL, OF VIENNA, AUSTRIA-HUNGARY.

DESIGN FOR A BOSOM-PROTECTOR.

SPECIFICATION forming part of Design No. 22,857, dated October 31, 1893.

Application filed September 14, 1893. Serial No. 485,511. Term of patent 7 years. Patented in Austria-Hungary, No. 3,909; in Switzerland, No. 6,320; in England, No. 18,278; in France, No. 225,330; in Belgium, No. 101,724; in Spain, No. 13,869; in Italy, No. 32,834, and in Norway, No. 2,873.

To all whom it may concern:

Be it known that I, MARIANNE BENDL, a subject of the Emperor of Austria-Hungary, residing in Vienna, in the Empire of Austria-Hungary, have invented and produced a new and original Design for Bosom-Protectors, (for which I have obtained patents in Austria-Hungary, No. 3,909, Tome 42/XXVI, folio 3,899; in Switzerland, No. 6,320; in England, No. 18,278; in France, No. 225,330; in Belgium, No. 101,724; in Spain, No. 13,869; in Italy, No. 32,834, and in Norway, No. 2,873,) of which the following is a specification.

Figure 1 is a front elevation of a bosom protector embodying my design. Fig. 2, is a rear and Fig. 3 is a side elevation of the same.

The leading features of this design consist in the conical raised front portions of the bosom protector, the ribbon like ornamentation of the arm and neck holes and the band like ornamentation of the lower edge of the protector.

In the drawings *a* represents the front of the bosom protector, which is provided with two conical shaped projections *c* ornamented ²⁵ by star like rows of stitching *d*. These conical projections are shown in side elevation in Fig. 3.

Around the edges of the arm holes are ribbon like ornamentations *e* and around the neck opening a ribbon like ornamentation *f*.

The lower edge of the bosom protector terminates in a broad band like ornament *b*.

What I claim is—

The design for a bosom protector, substantially as shown and described.

In testimony whereof I have signed this specification in the presence of two subscribing witnesses.

MARIANNE BENDL.
